B. P. JOYCE

GUN CARRIAGE

Filed Feb. 13, 1923

Inventor
Bryan P. Joyce

By
W. N. Roach.

Attorney

UNITED STATES PATENT OFFICE.

BRYAN P. JOYCE, OF DAVENPORT, IOWA.

GUN CARRIAGE.

Application filed February 13, 1923. Serial No. 613,648.

(FILED UNDER THE ACT OF MARCH 3, 1883, 22 STAT. L., 625.)

To all whom it may concern:

Be it known that I, BRYAN P. JOYCE, a citizen of the United States, and a resident of Davenport, county of Scott, and 5 State of Iowa, have invented an Improvement in Gun Carriages, of which the following is a specification.

The invention described herein may be used by the Government, or any of its officers or employees in prosecution of work for the Government, or by any other person in the United States, without payment to me of any royalty thereon, in accordance with the act of March 3, 1883.

15 The subject of this invention is a gun carriage and the invention relates more specifically to means for supporting the top carriage of a gun mount upon the bottom carriage.

20 In connecting the top and bottom carriages of a gun carriage in which the top carriage is intended to traverse or rotate about a pivot, it is desirable that the top carriage be so supported that it may traverse freely without undue friction between the moving members and yet the support be such that firing strains may be properly taken up by the more solid, substantial members of the structure. It is also essential that proper lubrication of all relatively 25 moving members be had.

30 The present invention is designed to provide a gun carriage having the above mentioned desirable features.

35 With the foregoing and other objects in view, the invention resides in the novel arrangement and combination of parts and in the details of construction hereinafter described and claimed, it being understood 40 that changes in the precise embodiment of the invention herein disclosed may be made within the scope of what is claimed without departing from the spirit of the invention.

45 A practical embodiment of the invention is illustrated in the accompanying drawing in which the figure is a substantially central vertical section of a fragment of a gun carriage constructed in accordance with my invention.

50 Referring to the drawing by numerals of reference:

In carrying out my invention I provide a bottom carriage 1 having a suitable aperture formed therein, the upper portion of

the aperture being enlarged to receive roller 65 bearings 2.

Upon the bottom carriage is mounted the top carriage 3 formed with a depending hollow pivot member 4 adapted to enter the aperture in the lower carriage and formed 60 with a lower portion of reduced diameter so as to provide an annular shoulder which seats upon the upper member 5 of ball race engaged by the balls 6 which are held in position thereagainst by a lower ball race 65 7 seated on a spring 8 which is supported on a ring 9 resting on an annular rib 10 formed on the bottom carriage and projecting into the aperture thereof. Interposed between the pivot member and walls of the 70 aperture of the lower carriage and positioned below the ring 9 are roller bearings 11 which take up side thrust of the top carriage.

75 Into the lower opened end of the pivot member is threaded a closure plug or nut 12 which holds the lower roller bearing assembled and which also contacts the bottom carriage and tends to draw the top carriage downwardly toward the bottom carriage 80 against the tension of the spring 8 thus bringing the spring to proper tension and allowing the upper carriage to engage a liner 13 interposed between the top and bottom carriages. The contact of the upper 85 carriage with the liner is adjusted so that a tilting movement of the upper carriage with respect to the bottom carriage is prevented but frictional contact of the upper carriage with the liner is at a minimum 90 thus allowing free traverse of the upper carriage upon the supporting ball bearings, but furnishing metal to metal contact to take up firing strains.

95 Secured to the closure nut 12 by and suitable means is a cylinder 14 which projects into the pivot member 4 and the upper end of which is apertured while its lower end is preferably open. The lower end of the cylinder is closed by a head 15 formed 100 with a tubular guide 16 in which the rod of a piston 17 may reciprocate, the piston being located within the cylinder and preferably formed with a suitable packing 18. The piston is normally urged upwardly 105 into the cylinder by means of a coil spring 19 to force grease through the opening in the top of the cylinder into the interior

of the pivot member and thence through the grease ports 20 and 21 to the various parts which need lubrication. Grease may be supplied to the interior of the pivot member and cylinder through a grease port 22 formed in the upper carriage.

I claim:

1. The combination with a bottom carriage, provided with an aperture formed at its upper end with an enlarged portion, of a top carriage, a hollow pivot member depending from the top carriage and positioned within the aperture, the lower portion of the pivot member of reduced diameter forming an annular shoulder, roller bearings in the enlarged portion of the aperture providing a side thrust bearing, ball bearings interposed between the pivot member and the wall of the aperture upon which the shoulder seats, a spring supporting the ball bearings, a ring supporting the spring, an annular flange on the bottom carriage supporting the ring, roller bearings below the ring and interposed between the pivot and the wall of the aperture, a closure plug threaded into the lower end of the pivot member and engaging the bottom carriage to draw the carriages together and properly

tension the spring, a cylinder carried by the plug and projecting into the pivot member, a piston in the cylinder, and resilient means for actuating the piston to automatically force grease to the members.

2. The combination with a bottom carriage provided with an aperture, of a top carriage provided with a grease port, a hollow pivot member depending from the top carriage and adapted to enter the aperture, roller bearings interposed between the pivot member and bottom carriage to take up lateral thrust, resiliently held ball bearings supporting the top carriage in traverse, means for adjusting the resiliency of the ball bearings and pressure means within the pivot member for supplying grease to the members.

3. The combination with a bottom carriage provided with an aperture, of a top carriage formed with a hollow depending pivot member adapted to enter the aperture, anti-friction bearings interposed between the pivot member and bottom carriage to take up lateral thrust and resiliently held anti-friction bearings supporting the top carriage in traverse.

BRYAN P. JOYCE.
